Original application December 16, 1938, Serial No.
246,236. Divided and this application August
16, 1939, Serial No. 290,462

14 Claims. (Cl. 22—82)

5

This invention relates to a crucible support and is a division of my copending application Serial No. 246,236, filed December 16, 1938.

In my copending application referred to I have disclosed a crucible support adapted for use with relatively heavy crucibles and having means associated therewith to facilitate the tilting of the crucible to a pouring position, together with means normally latching the crucible against tilting movement, and means for connecting a handle to the tilting structure to facilitate the pouring of the crucible, the handle having means for preventing accidental dislodgement thereof during the pouring operation.

15 An important object of the present invention is to provide screw actuated means of a novel type for moving the jaws into engagement with the crucible.

A further object is to provide such a mechanism 20 in combination with other related features whereby the jaw operating mechanism and associated parts combine to form a rigid unitary tilting structure particularly adapted for use with relatively large heavy crucibles.

25 A further object is to provide a pair of levers having crucible-engaging jaws at their lower ends, a supporting structure for the levers and screw actuated means for operating the levers to move the jaws into engagement with the crucible, the 30 screw means being associated with the supporting structure to be positioned thereby and to facilitate the uniting of the parts into a unitary tilting structure when it is desired to pour metal from the crucible.

35 A further object is to provide such a combined structure with means for supporting the crucible supporting structure for tilting movement to facilitate the pouring of the metal from the crucible.

40 Other objects and advantages of the invention will become apparent during the course of the following description.

In the drawings I have shown one embodiment of the invention. In this showing:

45 Figure 1 is a front elevation of the mechanism showing a crucible supported thereby.

Figure 2 is a sectional view taken on line 2—2 of Figure 1.

50 Figure 3 is a sectional view taken on line 3—3 of Figure 1.

Figure 4 is a sectional view taken on line 4—4 of Figure 1, parts being shown in elevation and parts being broken away.

55 Figure 5 is a sectional view taken on line 5—5 of Figure 1, and,

Figure 6 is a detail perspective view of one of the crucible-engaging jaw elements.

Referring to the drawings, the numeral 10 designates a crucible supported by an article supporting unit indicated as a whole by the numeral 11. This unit is rotatably carried by a supporting structure indicated as a whole by the numeral 12 for turning or tilting movement relative thereto in a manner to be described.

The supporting unit 11 comprises a vertical member 13 and oppositely projecting integral parallel horizontal members 14 rigidly formed on the lower end thereof. The ends of the horizontal members 14 are turned downwardly to provide depending pairs of spaced vertical members 16.

A pair of arms 18 are respectively pivoted to the pairs of vertical members 16 by bolts 20, each arm 18 lying between the members of the associated pair 16 for a purpose to be described. Crucible gripping members 21 are carried by the lower ends 20 of the arms 18 and are movable into or out of engagement with the crucible 10 upon pivotal movement of the arms 18 about the pivot bolts 20. The members 21 are detachably connected to the arms 18 in a manner to be described.

25 A shaft 23 is provided to effect pivotal movement of the arms 18 and a consequent movement of the crucible gripping members 21 into or out of engagement with the crucible 10. The vertical member 13 of the supporting unit 11 provides a 30 journal 24 for the shaft 23. Endwise movement of the shaft 23 relative to the vertical member 13 is prevented by collars 25 which are secured to the shaft 23 by pins 27, the collars 25 abutting vertical faces of the member 13. The respective 35 ends 29 and 30 of the shaft 23 are threaded in opposite directions to provide conventional right hand threads on the end 29 and left hand threads on the end 30. The shaft 23 is preferably squared at both ends as at 31 in order that a wrench may 40 be used at either end of the shaft to rotate it.

45 Trunnion cradles 33 are provided on the respective upper ends of the arms 18. Each of the trunnion cradles 33 is provided with spaced pairs of vertical members 35 to receive trunnions 36. 45 The trunnions are carried by sleeves 37 internally threaded for engagement with the threaded portions of the shaft 23. Bolts 40 extend through the members 35 transversely of the trunnions 36 to prevent disengagement thereof from the respective cradles 33 and 34.

50 By reason of the oppositely threaded ends 29 and 30 of the shaft 23 having engagement with the internally threaded sleeves 37, it will be apparent that rotation of the shaft 23 will cause 55

5 pivotal movement of the members 18 about the bolts 20 in a manner which will effect simultaneous movement of the crucible gripping members 21 into or out of engagement with the crucible 10.

10 The gripping members 21 are frictionally engageable with the sides of the crucible 10 and have their gripping surfaces shaped to conform to the shape of the crucible. Each of the gripping members 21 is removably secured to the lower ends of one pair of the members 18 in order that various sizes of the gripping members may be used according to the crucible to be supported thereby. Each of the gripping members 21 is provided with a pair of lugs 41 spaced from each other a distance approximately equal to the thickness of each of the members 18. Abutments 42 are formed on the lower ends of the members 18 and for the purpose of providing a key fit of the lugs 41 with the abutments 42, it will be noted that the contacting faces of these elements slope inwardly and upwardly as at 43 toward the article to be engaged. Openings 44 are formed in the members 18 to receive wedges 45 which are driven into engagement with the upper edges of the lugs 41 to securely hold the lower edges thereof in engagement with the abutments 42. The mechanism for detachably securing the gripping members to their supporting members is illustrated and described in my copending application Serial No. 232,005, filed September 27, 1938.

30 Means are preferably provided to properly position the members 21 with respect to the side of the crucible. To this end, an adjustable positioning plate 46 is provided which may be brought into contact with the top 47 of the crucible. Pairs of fingers 48 are formed on the plate 46 and are spaced to provide elongated slots 49. The fingers 48 are positioned and slideable between the members 14 in order that the plate 46 and the top of the crucible 47 will be properly positioned relative to the supporting unit 11 according to the size of the crucible to be supported. To secure the plate 46 to the arms 14, bolts 50 are provided which pass through the slots 49. The bolts 50 are provided with enlarged rectangular heads 51 which frictionally engage the fingers 48 as at 52. Openings are provided in one of the arms 14 corresponding to the shape of the heads 51 to prevent turning movement of the bolts 50 relative to the members 14. Nuts 53 are provided for the purpose of securely clamping the fingers 48 and plate 46 in any desired position according to the size of the crucible to be used. The mechanism for positioning the gripping members relative to the top 47 of the crucible 10 is described in my above mentioned copending application.

60 In order that the crucible 10 after its removal from a furnace may be tilted to pour molten metal therefrom, it is desirable to connect the supporting unit 11 for turning movement relative to the supporting structure 12. To this end, a trunnion 54 is preferably formed integral with each pair of vertical members 16. The trunnions 54 are provided with circumferential grooves 55 which provide circular trackways for the lower looped ends of substantially U-shaped members 56 connecting the crucible supporting unit 11 to the supporting structure 12 in a manner to be described.

65 The supporting structure 12 comprises a horizontal member 58 provided with an eye 59 which may be connected to a hook 60 of any suitable

5 lifting apparatus. The members 56 are formed from metal rods which are doubled back on themselves and are suspended from the horizontal member 58 by nuts 61. Lock nuts 62 are provided to prevent upward movement of the members 56 relative to the horizontal member 58. By doubling the rods 56 back on each other, the ends of each rod, which are connected to the horizontal member 58, are parallel to and spaced from each other and the mid-portions 63 are 10 formed in the shape of a semi-circle for sliding engagement with the groove 55. Spacing members 65 are connected between the parallel portions of each of the members 55 immediately above the trunnions 54 to prevent any spreading 15 motion of the parallel portions of the members 56 adjacent the trunnions 54 which would permit disengagement of the semi-circular portions of the members 56 from the circular grooves 55.

20 It will be seen that the above described arrangement provides a pivotal support in the nature of a trunnion for the crucible supporting unit 11. However, it is desirable that the crucible supporting unit 11 may be rotated relative to the supporting structure 12 with a minimum of 25 effort and, accordingly, the horizontal axis 66 of the trunnions 54 about which the turning movement takes place is preferably located adjacent the center of gravity of the supporting unit 11 and the crucible 10 supported thereby. 30 Moreover, it is desirable that the unit 11 and the crucible 10 normally occupy a vertical position relative to the supporting structure 12 and, accordingly, the horizontal axis 66 is preferably located slightly above the center of gravity of 35 the unit 11 and the crucible 10 supported thereby.

40 A handle 67 is provided to enable an operator to tilt the crucible for the purpose of pouring molten metal therefrom. The handle 67 has a cylindrical opening 68 formed in one end thereof for engagement with a member 69 projecting from the vertical member 13 of the supporting unit 11. The member 69 is secured to the vertical member 13 by any suitable means such as the 45 rivets 70.

45 A collar 71 is formed on the end of the handle 67 and is engageable with a detent 72 to prevent disengagement of the lever 67 from the member 69 during that time in which the crucible 50 10 is tilted to pour metal therefrom. The detent 72 is pivotally connected to the vertical member 13 by a pivot pin 73 and is provided with a counterweight 74 which will maintain the point 72' of the detent 72 in constant engagement 55 with the handle 67. Any disengaging movement of the lever 67 from its support 69 will operate to jamb the collar 71 against the point 72' of the detent 72, and to remove the lever 67 it will first be necessary to raise the counterweight 74 60 and thereby allow the collar 71 to clear the point 72' on the detent 72. It will be apparent that this arrangement will securely prevent disengagement of the lever 67 from the member 69.

65 During the removal of the crucible 10 from a furnace, it is desirable to provide means for retaining the unit 11 in a substantially vertical position relative to the supporting structure 12. To this end, an abutment 75 is preferably formed integral with the horizontal member 58 70 for the purpose of preventing turning movement of the unit 11 to the right, as viewed in Figure 4, at all times. A gravity actuated pawl 76 is also connected to the horizontal member 58 for normally preventing turning movement of the unit 75

11 in the opposite direction. The pawl 76 is mounted on the horizontal member 58 by a plate 77 which permits sliding movement of the pawl 76 relative to the horizontal member 58. A handle 78 is provided to enable an operator to raise the pawl 76 to permit turning movement of the unit 11 to the left, as viewed in Figure 4. The plate 77 is provided with a slot 79 through which the handle 78 protrudes whereby manual actuation of the pawl 76 will be permitted.

In order that the unit 11 may be returned to its normal vertical position and locked in such position without the necessity of actuating the pawl or latch 76, the upper surface 80 of the member 13 is inclined to provide a cam surface as shown in Figure 4. The bottom edge 81 of the pawl 76 has a similar inclination or is rounded to secure a camming action which will cause the pawl 76 to automatically ride up the surface 80 upon return of the unit 11 to its normal vertical position. It will be apparent that the latch 76 will drop to lock the unit 11 in its normal vertical position as soon as such position is reached.

25 The operation of the apparatus is as follows:

The plate 46 is adjusted in order that the gripping members 21 will be properly positioned relative to the sides of the crucible. When the parts of the apparatus are in normal position, the latch 30 16 will be operative to prevent turning movement of the crucible supporting unit 11 relative to the supporting structure 12.

The mechanism may be lowered by the hook 60 until the plate 46 contacts the upper edge 47 of the crucible 10. The mechanism will then be in a position for the gripping members 21 to properly engage the sides of the crucible 10. This is accomplished by applying a wrench to either end 31 of the shaft 23 and rotating this 40 shaft to cause movement of the trunnions 36 away from each other. It will be noted that the shaft 23 has its polygonal ends 31 arranged between the arms 56 of the respective pairs of supporting rods, thus facilitating the application 45 of a wrench to either of the polygonal ends of the shaft. Outward movement of the trunnions 36 in the manner described will impart a similar movement to the cradles 33 on the respective upper ends of the pivotally mounted members 18 50 whereby the crucible gripping members 21 on the respective lower ends of the members 18 will be moved into engagement with the crucible 10. In such position the apparatus is operable to furnish a support by which the crucible can be 55 transported.

It will be noted that the vertical member 13 provides effective bearing means for supporting and positioning the shaft 23. This shaft accordingly is fixed against vertical movement, 60 while the trunnions 36, during the operation just described, will move in arcuate paths about the axes of the bolts 20. While the swinging movement of the levers 18 is limited, the trunnions 36 have some slight vertical component of 65 movement, and this is compensated for by the slots provided between the pairs of vertical members 35, the trunnions 36 being capable of partaking of relative vertical movement within reasonable limits between the members 35.

70 When it is desired to tilt the crucible for the purpose of pouring molten metal therefrom, the operator will slip the open end 68 of the handle 67 downwardly over the projecting member 69 secured to the supporting unit 11. It will be apparent that prior to such application of the han-

75 dle 67 to the member 69, the point 72 on the detent 72 will have been in engagement with the member 69. Upon downward movement of the handle 67 relative to the member 69, the collar 71 will contact the detent 72 and cam the same 10 out of engagement with the member 69. As soon as the collar 71 passes the point 72 on the detent 72, the counterweight 74 will cause a pivotal movement of the detent 72 into engagement with the handle 67 at a point above the collar 71. In 15 this position, it will be apparent that the detent 72 will be operable to prevent accidental disengagement of the lever 57 from the member 69.

Before a turning or tilting movement can be imparted to the crucible supporting unit 11 relative to the supporting structure 12, it will be necessary for the operator to raise the handle 18 and latch 76. After releasing the latch 76 from engagement with the crucible supporting unit 11, the latter and the crucible supported thereby may 20 be rotated to a position such as that shown in dotted lines in Figure 4 for the purpose of pouring molten metal.

Particular attention is invited to the latching of the handle 67 to the projection 69. I am aware 25 that detachable handles have been used with prior constructions for tilting crucibles to pouring position, but such prior constructions have been found to be highly disadvantageous. When an operator grasps a crucible-tilting handle when 30 the latter is in such a position as the solid line position shown in Figure 4, a downward pull on the handle tends more firmly to engage the handle with the projection 69 or corresponding element. When the pouring position is reached, however, 35 it has been found that with prior constructions an operator sometimes will accidentally or carelessly exert a pull on the handle in the direction of the free end thereof. In prior constructions, therefore, handles have become disconnected 40 from the crucible supporting means, thus permitting the crucible to suddenly swing back toward its normal or vertical position, resulting in the splashing of molten metal from the crucible and frequently resulting in injury to the operator. 45

It obviously is desirable that the operator exert a force at right angles to the handle 67 to tilt the crucible, and if this operation is carefully performed, there is no danger that the handle will become detached. Carelessness in handling an 50 apparatus of this character is frequent, however, and in order to prevent injury to an operator or other nearby workman, the present construction provides means for positively preventing accidental detachment of the handle 67 from the projection 69. Regardless of any endwise pull on the handle 69, the engagement of the flange 71 with the detent 72 will positively prevent detachment of the handle, and accordingly the crucible cannot swing back to its normal position except 60 under the control of the operator. Thus the apparatus provides means for preventing serious and painful injuries to operators. 65

Particular attention is invited to the screw actuating means for the levers 18 and the elements associated therewith. The shaft 23 is rotatably supported and positioned by the vertical member 13, which is a rigid part of the supporting unit 11. When the upper ends of the levers 18 are moved outwardly and the jaws 21 engage the 70 crucible, the shaft 23 forms an effective connection between the upper ends of the levers 18 and the supporting unit 11, thus assisting in providing a tilting unit the parts of which are very efficiently rigidly fixed with respect to each other. 75

This rigidity of the elements of the tilting unit with respect to each other is increased by the arrangement of the levers 18 between the arms 16 of the respective pair at opposite sides of the supporting unit.

Referring to Figure 3 it will be noted that the levers 18 are only provided with clearance between the elements to which they are connected, and when a pull is exerted on the handle 67 (Figure 4) the arrangement of the parts referred to effectively prevents any tilting movement of the members 14 and 16 with respect to the levers 18. It is highly important in a structure intended for handling heavy crucibles that the parts be rigidly positioned with respect to each other, and this is accomplished in the present mechanism with a relatively simple construction.

After a pouring operation has been completed, the operator may reduce the pull on the handle 67 to permit the parts to swing back to their normal position. As such position is approached, the cam face 30 will engage and lift the latch 76, and when the vertical member 13 reaches its normal position, the latch 76 will drop to operative position and the entire crucible supporting unit 11 will be prevented from swinging. The handle may be readily detached, when desired, by manually lifting the counterweight 74 to move the detent 72 away from the flange 71, whereupon the handle may be moved endwise to disconnect it from the projection 69.

It will be apparent that the apparatus herein illustrated and described furnishes a convenient means for supporting a crucible. By having the crucible supporting mechanism rotatably mounted with respect to a supporting structure, a convenient means for pouring molten metal from the crucible is provided. In addition, the locking mechanism is effective to prevent any uncontrolled movement of the crucible supporting unit relative to the supporting structure.

It is to be understood that the form of the invention herewith shown and described is to be taken as a preferred example of the same and that various changes in the shape, size and arrangement of parts may be resorted to without departing from the spirit of the invention or the scope of the subjoined claims.

I claim:

1. A device of the character described comprising a supporting structure, a pair of members provided with article gripping devices on the lower ends thereof, each of said members being pivotally connected to said structure to swing on horizontal axes, and actuating mechanism for said members comprising a threaded shaft, and means directly connecting said shaft to the upper ends of said members whereby rotation of said shaft will cause movement of said gripping devices toward or away from each other.

2. A device of the character described comprising a supporting structure, a pair of members provided with article gripping devices on the lower ends thereof, each of said members being pivotally connected to said structure to swing on horizontal axes, and actuating mechanism for said members comprising a shaft having oppositely threaded ends and means directly connecting the upper ends of said members to the ends of said shaft respectively whereby rotation of said shaft will cause movement of the gripping devices toward or away from each other.

3. A device of the character described comprising a supporting structure, a pair of members provided with article gripping devices on the

lower ends thereof, each of said members being pivotally connected to said structure, and actuating mechanism for said members comprising a shaft having oppositely threaded ends, a pair of sleeves each having trunnions and being threaded on one end of said shaft, and a trunnion-cradle formed on the upper end of each of said members, said trunnion-cradles carrying said trunnions whereby rotation of said shaft will cause movement of said gripping devices toward or away from each other.

4. A device of the character described comprising a supporting structure having a rigid upstanding member, a pair of levers provided with article gripping devices at their lower ends, said levers being pivotally connected to said structure, and actuating mechanism for said levers comprising a shaft rotatably supported intermediate its ends by said upstanding member, and means connecting said shaft on opposite sides of said upstanding member to the upper ends of said levers whereby rotation of said shaft will cause movement of said gripping devices toward and away from each other.

5. A device of the character described comprising a supporting structure having a rigid upstanding member, a pair of levers provided with article gripping devices at their lower ends, said levers being pivotally connected to said structure, and actuating mechanism for said levers comprising a shaft rotatably supported intermediate its ends by said upstanding member, the ends of said shaft being oppositely threaded, and a sleeve threaded on each end of said shaft and connected to the upper end of one of said levers whereby rotation of said shaft will cause movement of said gripping devices toward and away from each other.

6. A device of the character described comprising a supporting structure having a rigid upstanding member and a pair of spaced depending arm structures each of which is formed of a pair of parallel elements, a pair of levers having article gripping devices at their lower ends, each lever being pivotally connected to one of said arm structures and mounted between the parallel elements thereof, and means for moving the upper ends of said levers toward and away from each other to effect similar movement of said gripping devices.

7. A device of the character described comprising a supporting structure having a rigid upstanding member and a pair of spaced depending arm structures each of which is formed of a pair of parallel elements, a pair of levers having article gripping devices at their lower ends, each lever being pivotally connected to one of said arm structures and mounted between the parallel elements thereof, and a turnbuckle shaft having connection at its end portions with the upper ends of said levers to effect movement of said gripping devices toward and away from each other.

8. A device of the character described comprising a supporting structure having a rigid upstanding member and a pair of spaced depending arm structures each of which is formed of a pair of parallel elements, a pair of levers having article gripping devices at their lower ends, each lever being pivotally connected to one of said arm structures and mounted between the parallel elements thereof, and actuating mechanism for said levers comprising a shaft rotatably supported by said upstanding member and fixed with respect thereto against axial movement, and means connecting said shaft to the upper ends of said levers

whereby rotation of said shaft will cause movement of said gripping devices toward and away from each other.

9. A device of the character described comprising a supporting structure having a rigid upstanding member and a pair of spaced depending arm structures each of which is formed of a pair of parallel elements, a pair of levers having article gripping devices at their lower ends, each lever being pivotally connected to one of said arm structures and mounted between the parallel elements thereof, and actuating mechanism for said levers comprising a shaft rotatably supported by said upstanding member and fixed with respect thereto against axial movement, the end portions of said shaft being oppositely threaded, and a sleeve threaded on each end of said shaft and connected to the upper end of one of said levers whereby rotation of said shaft will cause movement of said gripping devices toward and away from each other.

10. A device of the character described comprising a supporting structure having a rigid upstanding member and a pair of spaced depending arm structures each of which is formed of a pair of parallel elements, a pair of levers having article gripping devices at their lower ends, each lever being pivotally connected to one of said arm structures and mounted between the parallel elements thereof, and actuating mechanism for said levers comprising a shaft rotatably supported by said upstanding member and fixed with respect thereto against axial movement, the end portions of said shaft being oppositely threaded, a sleeve threaded on each end portion of said shaft and provided with outstanding trunnions, and a connection on the upper end of each lever receiving the trunnions of the adjacent sleeve whereby said sleeves will actuate said levers upon rotation of said shaft to effect movement of said gripping devices toward and away from each other.

11. A device of the character described comprising a supporting structure having a rigid upstanding member and a pair of depending spaced arms, a pair of levers provided with article gripping devices at their lower ends, said levers being respectively pivotally connected to the lower ends of said arms to swing in a common vertical plane, a shaft arranged approximately in the plane of said levers, said shaft being pivotally supported by said upstanding member and fixed thereby against axial movement, the ends of said shaft being oppositely threaded, means connecting the respective ends of said shaft to the upper ends of said levers to impart swinging movement thereto upon rotation of said shaft, and means arranged wholly outwardly of said arms and said levers for supporting them for bodily rocking movement on a horizontal axis approximately in the plane of swinging movement of said levers.

12. A device of the character described comprising a supporting structure having a rigid upstanding member and a pair of depending

spaced arms, a pair of levers provided with article gripping devices at their lower ends, said levers being respectively pivotally connected to the lower ends of said arms to swing in a common vertical plane, a shaft arranged approximately in the plane of said levers, said shaft being pivotally supported by said upstanding member and fixed thereby against axial movement, the ends of said shaft being oppositely threaded, a sleeve threaded on each end of said shaft, a connection between each sleeve and the upper end of the adjacent lever whereby axial movement of said sleeves incident to rotation of said shaft will effect swinging movement of said levers, and means arranged wholly outwardly of said arms and said levers for supporting them for bodily swinging movement on a horizontal axis lying approximately in the plane of swinging movement of said levers.

13. A device of the character described comprising a supporting structure having a rigid upstanding member and a pair of depending spaced arms, a pair of levers provided with article gripping devices at their lower ends, said levers being respectively pivotally connected to the lower ends of said arms to swing in a common vertical plane, a shaft arranged approximately in the plane of said levers, said shaft being pivotally supported by said upstanding member and fixed thereby against axial movement, the ends of said shaft being oppositely threaded, means connecting the respective ends of said shaft to the upper ends of said levers to impart swinging movement thereto upon rotation of said shaft, trunnions fixed with respect to said supporting structure and having a common horizontal axis lying approximately in the plane of swinging movement of said levers and arranged wholly outwardly of said arms and said levers, and means rotatably supporting said trunnions.

14. A device of the character described comprising a supporting structure having a rigid upstanding member and a pair of depending spaced arms, a pair of levers provided with article gripping devices at their lower ends, said levers being respectively pivotally connected to the lower ends of said arms to swing in a common vertical plane, a shaft arranged approximately in the plane of said levers, said shaft being pivotally supported by said upstanding member and fixed thereby against axial movement, the ends of said shaft being oppositely threaded, a sleeve threaded on each end of said shaft, a connection between each sleeve and the upper end of the adjacent lever whereby axial movement of said sleeves incident to rotation of said shaft will effect swinging movement of said levers, trunnions fixed with respect to said supporting structure and having a common horizontal axis lying approximately in the plane of swinging movement of said levers and arranged wholly outwardly of said arms and said levers, and means rotatably supporting said trunnions.

RAYMOND D. YORK.
